CLAMPING DEVICE

Felix J. Stuckert, Wauwatosa, Wis., assignor to
 Briggs & Stratton Corporation, Milwaukee,
 Wis., a corporation of Delaware

Application April 13, 1940, Serial No. 329,485

9 Claims. (Cl. 90—60)

This invention relates generally to clamps of the type employed to securely hold work to a supporting surface while machining operations are performed on the work.

At present various types of clamps are employed for this purpose, the most common of which are the strap and angle iron types. Strap type clamps employ a bar to bridge the space between an article on a work table and a block placed on the table adjacent to the article and effect clamping by tightening a stud or bolt anchored in the work table and extending through the strap.

In the angle iron type the strap is angle shaped, and has one leg or flange of the angle abutting the supporting surface while the end of its opposite flange engages the work on the support. In this form the clamp is also tightened by means of a stud or bolt anchored in the support and received in the work engaging flange of the clamp.

While clamps of this type effectively maintain the work tightly secured with respect to the work table, they are not suited for such use when production methods of machining are employed as the constant necessity of tightening and loosening screws and sometimes removal of the strap consumes an excessive amount of time during application and release of the clamp.

With this objection to past clamping devices in mind, this invention has as a general object to provide a clamping device for the purpose described which may be quickly operated to releasably clamp work to a support without entailing tightening of screws or removal of the clamp from the supporting surface.

Another object of this invention resides in providing a clamping device of the character described with a clamping lever projectable manually to and from an operative clamping position with respect to an article to be clamped.

Still another object of the invention resides in the provision of a clamping device of the character described with a pivoted clamping lever which may be projected bodily outwardly of the device to an operative position over work to be clamped and thereafter tilted on its pivot toward the work in a clamping relationship therewith.

A further object of this invention is to provide a manually operable clamping device of the character described with actuating means adapted to successively project the clamping lever outwardly of the device to an operative position over the work to be clamped and then force the lever into clamping engagement with the work

in one continuous operation of the actuating means.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a perspective view of the clamping device of this invention with a part thereof broken away and in section;

Figure 2 is a longitudinal sectional view illustrating the inactive position of the clamping lever of the device;

Figure 3 is a sectional view similar to Figure 2 illustrating the active position of the clamping lever of the device;

Figure 4 is a transverse sectional view taken through Figure 2 on the plane of the line 4—4 and

Figure 5 is a fragmentary perspective view illustrating portions of the clamping device.

Referring now particularly to the accompanying drawing in which like numerals indicate like parts, the numeral 10 generally designates the clamping device of this invention. As is customary, the clamping device is used to firmly hold an article of work indicated in construction lines as at 11 to the work table of the machine which is to perform the machining operations on the article. The clamping device may be used in conjunction with a work locating fixture or template 12, or it may be used merely to hold the work indiscriminately to the work table.

As illustrated, the clamping device 10 comprises a supporting structure 13 which includes a flat base 14 and spaced arms 15 and 16 projecting upwardly from the front end of the base. A clamping lever 17 is positioned between the arms and comprises a substantially T-shaped member having its forward end slidably confined between the arms and its T-shaped rear end overlying the base.

The clamping lever is slidably supported above the top face of the base by means of a pair of adjustable screws 18 passing through the op-

posite ends of the T-shaped portion of the clamping lever with their ends engageable directly with the top surface of the base.

A leaf spring 19 secured to the base with its free end engaging under the forward end of the clamping lever, cooperates with the screws 18 to tiltly hold the clamping lever spaced above the top surface of the base.

The clamping lever 17 is thus free to slide forwardly and backwardly across the top of the base between the upright arms 15 and 16.

The clamping lever 17 is yieldingly maintained in a rearward or inactive position over the base by a pair of compression springs 20 disposed on opposite sides of the clamping portion of the clamping lever and having one end received in wells 21 in the rear edges of the arms 15 and 16. The other ends of the springs are received in recesses 22 in the T-shaped head of the clamping lever so that the springs at all times tend to slide the clamping lever rearwardly across the base.

A centrally located lug 23 at the rear of the base projects up into the path of rearward sliding motion of the clamping lever to limit the same. For this purpose, the T-shaped head is provided with a notch 24 to receive the lug therein in its rearward inactive position. Engagement between the lug and the bottom of the notch limits rearward sliding motion of the clamping lever, while the sides of the lug engage with the side walls of the notch to preclude lateral shifting of the clamping lever when retracted.

To effect forward propulsion of the clamping lever 17 an actuator including a cam-like pusher 26 is provided. The pusher 26 is supported between the arms 15 and 16 from a hexagonal shaft 27 having a circular bearing portion 28 at one end thereof journalled in the arm 16 and carrying a bushing 29 at its opposite hexagonal end which is journalled in the arm 15. The cam-like pusher is, therefore, drivingly connected with the hexagonal shaft 27 for rotation therewith.

As illustrated, the pusher 26 is notched as at 30 to provide a shoulder 31 at one end of the notch. As illustrated, the lower portion of the cam-like pusher member projects into a recess 32 cut into the side of the clamping lever so as to provide an abutment 33 facing the pusher shoulder 31 and in the path of the shoulder during rotation of the pusher member. Such rotation is imparted to the hexagonal shaft 27 and, consequently, the pusher member, by means of a hand lever 35 having a hexagonal hole 36 therein engageable over a hexagonal hub 37 on the bushing member 29. Consequently rotation of the hand lever in a clockwise direction as viewed in Figures 2 and 3 engages the shoulder 31 of the pusher member with the abutment 33 at the forward end of the recess in the side of the clamping lever and slides the clamping lever forwardly to a position in which its front end is above the work or article 11.

When the clamping lever is thus extended a cam 39, which may be formed either integrally with the pusher member 26 as shown or as a separate part on the shaft so as to be rotatable therewith is employed to tilt the forward end of the clamping lever downwardly toward the base 14 into clamping engagement with the article 11.

For this purpose, the cam 39 is provided with a concentric surface 40 with which the clamping lever normally engages, and an eccentric surface

41 which is brought into engagement with the clamping lever during clockwise rotation of the shaft and after the clamping lever has been fully projected by the pusher 26.

In this manner, one continuous motion of the hand lever to rotate the pusher and cam in a clockwise direction successively effects forward propulsion of the clamping lever with a translating motion and then tilting motion thereof toward the base and into clamping engagement with the work or article 11.

The motion imparted to the clamping lever by the cooperating pusher and cam actuating means is desirable in that it enables clamping of the work without any danger of the clamping lever shifting the same with respect to the work table or fixture upon which the work is positioned.

The clamping lever 17, it is to be noted, is at all times maintained in engagement with the cam 39 by the action of the leaf spring 19, which engages the clamping lever at a point such as to exert a turning moment on the clamp about the point of contact between the clamping lever and the periphery of the cam. Thus, the ends of the screws 18 are maintained in contact with the top face of the base and cooperate with the leaf spring 19 to freely tiltably and slidably mount the clamping lever.

The extent of forward propulsion of the clamping lever 17 is, of course, determined by the diameter or throw of the pusher member 26.

The actuating means for the clamping lever 17 is designed to operate the same during rotation of the hand lever through an angle of approximately 90°.

The forward end of the clamping lever is preferably provided with a toe 42 projecting from the underside of its forward end to facilitate clamping rough castings and to enable proper engagement of the clamping lever with the work in the event the article or jig therefor is provided with a rim or rib at its top periphery.

Release of the clamping device from the work upon completion of the machining operations is effected by an opposite or counterclockwise rotation of the hand lever 35 and consequently the actuating members 26 and 39. Thus, at the start of counterclockwise rotation of the lever the pressure of the clamping lever on the article 11 is gradually decreased inasmuch as such rotation of the cam 39 decreases the eccentricity of its periphery. Further rotation in this direction causes the shoulder 31 on the pusher member to again enter the recess 32. At this instant, the concentric surface of the cam 39 is brought into engagement with the clamping lever and the clamping lever is elevated to its fully raised position ready for retraction.

While the compression springs 20 at all times exert a force on the clamping lever tending to retract and maintain the same engaged with the pusher member 26, such action is prevented during release of the clamp and whenever the shoulder 31 is out of the recess 32 by the action of the leaf spring 19 which is compressed to a greater extent as long as the eccentric surface of the cam 39 is in contact with the upper face of the clamping lever. Thus a substantial friction is maintained at the point of contact between the clamping lever and the eccentric cam surface 41 which is sufficient to prevent the compression springs 20 from retracting the clamping lever until such time as the shoulder 31 of the pusher member again enters the recess

32 and the concentric surface of the cam engages the clamping lever.

As will be readily understood, the clamping device of this invention may be quickly adjusted toward and from the work table to accommodate articles of different thicknesses, and as shown, a shim 43 or a number of shims may be inserted between the work table and the bottom of the base of the clamping device for this purpose.

Tapped holes are provided in the bottom of the base to receive the threaded ends of screws 43' which detachably secure the clamping device to the work table of the machine as illustrated, or to the fixture 12 if provision for the clamping device is made therefor.

While the clamping device has been illustrated in use on a horizontal work table it is to be appreciated that it is equally well suited for use in a vertical position as when boring or similar operations are being performed on the article.

When so mounted, the hand lever 35 is preferably removed and adjusted angularly with respect to its hexagonal mounting 37 so as to facilitate turning the lever. For this purpose a screw 44 is provided which is threaded into the hexagonal end of the shaft 27 to detachably hold a washer 45 in place against the end of the hexagonal hub 37 and over the adjacent face of the hand lever 35.

From the foregoing description taken in connection with the accompanying drawing, it will be readily apparent that this invention provides a particularly efficient clamping device which is capable of rapid operation and which does not entail the tightening or loosening of screws by an operator during use thereof.

What I claim as my invention is:

1. In a clamping device of the character described: a clamping lever; means for movably supporting the clamping lever in spaced relation to a work supporting surface; and a manually movable actuator for moving said clamping lever successively outwardly of its support across said surface and downwardly onto an article on the work supporting surface to clamp work thereto during movement of the actuator in one direction.

2. In a clamping device of the character described: a base adapted to be secured to a work support adjacent to work thereon; a clamping lever; means supporting the clamping lever in spaced relation to the base and for movement across and toward the base; a single pivoted hand lever; and actuating means driven by the hand lever for moving the clamping lever successively outwardly across the base to a projected position in which a portion of the clamping lever overlies the work on the support and toward the base to effect clamping of the work between the work support and said portion of the clamping lever during one continuous motion of the hand lever.

3. In a clamping device of the character described: a base adapted to be secured on a work support adjacent to work thereon; a clamping lever; means supporting the clamping lever above the base for movement across and toward the base; a single hand lever mounted from the base for pivotal motion; actuating means driven by the hand lever operable in one continuous motion of the hand lever to move the clamping lever outwardly across the base to a projected position in which a portion of the clamping lever overlies the work on the support and to subsequently force the clamping lever toward the base to effect clamping of the work between the support and said portion of the clamping lever; and means

operable on the clamping lever to retract the same upon restoration of the hand lever and consequently the actuating means to their normal positions.

5. In a clamping device of the character described: a base; a pair of spaced apart arms extending upwardly from the base; a shaft having its opposite ends journaled in said arms for rotation about an axis spaced above the base; actuating means rotatable with the shaft and positioned between said arms; a slidable clamping lever overlying the base and having one end portion thereof disposed in the space between said arms and between the base and said actuating means; means biasing the clamping lever to a retracted position spaced above the base and engaging said actuator; an abutment on the clamping lever; a shoulder on said actuating means engageable with the clamping lever abutment during rotation of the shaft in one direction for sliding the clamping lever across the base to a projected position in which said end portion of the clamping lever overhangs the base; and means on said actuating means operable subsequently to such outward projection of the clamping lever and during continued rotation of the shaft in the same direction for forcing said clamping lever end portion toward the base in a clamping action.

30 5. In a clamping device of the character described: a base; a substantially T-shaped clamping lever; an adjustable abutment carried by each end of the T portion of the clamping lever in a position engaging the top face of the base so as to readily adjustably hold the T portion of the clamping lever a distance above the base; resilient means engaging the end of the clamping lever opposite its T portion and yieldingly urging said opposite end away from the base, said means cooperating with the abutments to mount the clamping lever for movement across the base and for movement of said opposite end thereof toward the base about an axis defined by the points of engagement of the adjustable abutments with the top face of the base; rotatable actuator mechanism for the clamping lever; a hand lever for rotating the actuator mechanism means on the actuator mechanism operable to move the clamping lever across the base to a projected position upon motion of the hand lever in one direction to rotate the actuator mechanism; and a cam forming a part of the actuator mechanism operable after completion of the motion of the clamping lever across the base and during continued motion of the hand lever in said direction to depress said opposite end of the clamping lever about the axis defined by the points of engagement between said abutments and the base.

6. In a clamping device of the character described: a base; spaced apart arms extending upwardly from the base; a substantially T-shaped clamping lever overlying the base with its stem disposed between said arms; cooperating means supporting the clamping lever above the base for movement across and toward the base; a compression spring on each side of the stem of the T-shaped clamping lever, each of said springs being confined between the side of the arm and the end of the T at opposite sides of the stem so as to yieldingly urge the T-shaped clamping lever in one direction with respect to the base; means on the base engageable with the clamping lever to limit movement thereof in said direction; and a rotatable actuator for the clamping lever operable upon rotation in a single direction to suc-

cessively effect movement of the clamping lever across the base in the opposite direction and depression of the lever toward the base.

7. In a device of the character described: a base; spaced apart arms extending upwardly from the base; a clamping lever; means supporting the clamping lever above the base for movement across and toward the base; a shaft rotatably journaled in said arms, said shaft having a medial portion of multiangular cross section; actuator mechanism on said portion of the shaft between the arms so as to be driven by the shaft; a hand lever mounted on an extension of the shaft outwardly of one of said arms of multiangular cross section for imparting rotation to the shaft and said actuator mechanism, said actuator mechanism including means for moving the clamping lever across the base and subsequently toward the base during rotation of the hand lever in a single direction; and means detachably securing the hand lever to the extension of the shaft whereby the hand lever is readily removable and adjustable angularly on said multiangular extension.

8. In a clamping device of the character described: a rigid supporting structure including a pair of spaced apart arms; a movable clamping lever having a portion at its forward end received between said arms to be guided for movement thereby; an abutment on each side of the rear end portion of the clamping lever, each of said abutments being adjacent to one edge of each arm; a compression spring disposed at each side of the clamping lever and confined between each of the arms and the abutments of the clamping lever adjacent thereto so as to yieldingly urge the clamping lever in one direction with respect to the arms; an actuator movably carried by the arms in the space therebetween; means carried by the supporting structure for 40

yieldingly urging the clamping lever toward engagement with said actuator; and means on the actuator operable upon motion thereof in one direction to move the clamping lever in a direction against the force of said compression springs and subsequently force the clamping lever in a direction away from the actuator against its yielding means.

9. In a clamping device of the character described: a supporting structure including a base adapted to be secured to a work table adjacent to work thereon and spaced apart arms extending upwardly from the base; a movable clamping lever having a portion at its forward end received between said arms to be guided thereby for movement across and toward the base; actuator mechanism movably carried by the arms in the space therebetween; a hand lever carried by the supporting structure for imparting motion to the actuator mechanism; means on the supporting structure for yieldingly urging the clamping lever toward engagement with the actuator mechanism and spaced away from the base; means on the actuator mechanism operable to move the clamping lever across the base to a position in which its forward end portion is projected and overlies the work on the table and to subsequently force the clamping lever toward the base and into clamping relationship with the work on the table upon motion of the actuator mechanism produced by motion of the hand lever in one direction; and a toe projecting from the underside of the forward end portion of the clamping lever engageable with the work during motion of the clamping lever toward the work to confine contact between the clamping lever and the work to a small area of the clamping lever.

FELIX J. STUCKERT.
